UNITED STATES PATENT OFFICE.

EDMUND C. MORGAN, OF CHICAGO, ILLINOIS; OLIVE EUGENIE MORGAN EXECUTRIX
OF SAID EDMUND C. MORGAN, DECEASED.

MACHINE FOR MINING.

Application filed January 5, 1916. Serial No. 70,341.

To all whom it may concern:

Be it known that I, EDMUND C. MORGAN, a citizen of the United States, residing at Chicago, in the county of Cook and State of Illinois, have invented certain new and useful Improvements in Machines for Mining, of which the following is a specification.

This invention relates to improvements in mining machines and mining systems and has for its object the provision of a machine of this character which shall be of novel and improved construction and operation. The invention also contemplates the new system embodying my improved machine.

This invention is exemplified in the combination and arrangement of parts, and the method of operation, illustrated in the accompanying drawings and described in the following specification, and it is more particularly pointed out in the appended claims.

In the drawings,—

Fig. 1 is a diagrammatic plan view of the arrangement of a mine, illustrating the method of operation forming a part of this invention;

Fig. 2 is a view similar to Fig. 1 but differing from Fig. 1 in that it shows only a small portion of a mine on a larger scale;

Fig. 3 is a top plan view of the machine for severing the coal from its native bed which forms a part of this invention;

Fig. 4 is an end elevation of the machine shown in Fig. 3, the operating portion of the machine being in its upper position;

Fig. 5 is a side elevation of the machine shown in Fig. 4, but with the operating part in its lower position;

Fig. 6 is a fragmentary top plan view of the operating mechanism of the machine shown in Fig. 3;

Fig. 7 is a sectional elevation of the machine shown in Fig. 6;

Fig. 8 is a plan view of the upper end of the supporting standard of the machine shown in Fig. 7;

Fig. 9 is a section on line 9—9 of Fig. 7;

Fig. 10 is an elevational view with parts in section, of the mining machine, showing the construction of the operating engine;

Fig. 11 is a vertical sectional view of the upper end of one form of the supporting standard for the mining machine;

Fig. 12 is a fragmentary bottom plan view of the head for the supporting standard shown in Fig. 11;

Fig. 13 is a fragmentary sectional view on line 13—13 of Fig. 7;

Fig. 14 is a fragmentary sectional view on line 14—14 of Fig. 13;

Fig. 15 is an elevational view of the planetary gearing used in connection with the mechanism shown in Fig. 13;

Fig. 16 is a sectional view of the supply coupling for the energizing fluid used to drive the engine of the mining machine;

Fig. 17 is a transverse sectional view of a mine showing a supporting prop used in connection with this invention;

Fig. 18 is a diagrammatic sectional plan view illustrating the method of shifting the supporting props;

Fig. 19 is a transverse sectional view of a mine entry illustrating one step in the process forming a part of this invention;

Fig. 20 is a view of the entry shown in Fig. 19, illustrating a subsequent step to that shown in Fig. 19;

Fig. 21 is a vertical sectional view of one form of mine prop used in connection with this invention;

Fig. 22 is a detail view of one of the valves of the prop shown in Fig. 21;

Fig. 23 is a horizontal sectional view of the prop shown in Fig. 21;

Fig. 24 is a detail view of another valve of this prop;

Fig. 25 is a sectional view of a modified form of mine prop;

Fig. 26 is a bottom plan, and

Fig. 27 is a top plan, of a combined pump and windlass used in shifting the mine props as shown in Fig. 18.

In order that the invention may be best understood, the machine used in the process of mining to sever the coal from its native bed will first be described. This machine is best illustrated in Figs. 3 to 16, inclusive. Referring to these figures, the numeral 1 designates a supporting standard having a widely extending circular base 2 and provided with peripheral screw threads 3. This standard is made hollow, as indicated at 4, and is provided with keyways 5 and keys 6 at the upper end thereof for the purpose of

securing thereto extension members 7. The extension members 7 have downwardly extending portions 8 which fit into the upper end of the opening 4 and are provided with 5 keyways to register with the keys 6 carried by the upper portion of the standard. The extensions are provided with threads 9 arranged to form a continuation of the threads 3 of the standard proper. As many extensions 10 may be provided as is found necessary, the number depending upon the height of the mine chamber in which the machine is being operated. The nature of these extensions will depend upon the conditions of 15 operation. In the form shown in Fig. 7, the extension 7 is given the character of a hydraulic jack having a plunger 10, which may be forced upwardly in a cylindrical portion 11 of the extension by means of a 20 liquid 12 confined within the cylindrical portion. The hydraulic jack may be of ordinary construction and provided with a stub shaft 13, to which the handle for operating the jack may be detachably secured. 25 The upper end of the extension 7 is provided with keyways 14 to register with keys 15 carried by the head 16 of the jack. By this construction, the head 16 may be forced upwardly relative to the standard 1, 30 but is held from rotation relative thereto. The head 16 is provided with the laterally radial extending arms 17 having projecting lugs 18 arranged to be forced into the upper surface of the mine chamber. These 35 lugs 18 prevent any rotation of the head 16 and also of the standard 1 when the device is secured in operative position. Slots 19 are provided in the upper end of the extension 7 to receive the arms 17 when the 40 head of the jack is lowered. These slots are made deep enough to permit of sufficient clearance above the upper end of the extension 7 to allow the downwardly extending portion 8 to be withdrawn from the upper 45 end of the standard 1, so that the extension may be removed from the supporting standard when it is desirable to do so. In very shallow veins a screw-threaded head 16', Fig. 11, operated by hand wheel 16'', is employed.

A framework 20 for carrying the operating mechanism of the machine is associated with the standard 1 and is provided with upper and lower guide portions 21 and 22, which have circular openings 23 and 24, respectively, which fit over the standard 1 and are of the proper diameter to slide freely on the outer periphery of the screw threads carried by the standard. Threaded 55 on the standard 1 and positioned just above the lower guide member 22, is a nut 25 which is provided with teeth 26 on its periphery, thus forming a worm wheel. Resting on the upper surface of the nut 25 and splined to the supporting standard 1 is a 60 second worm wheel 27, free to slide vertically upon the standard but prevented from rotation thereon by keys 28. The upper surface of the worm wheel 27 contacts with the lower surface of the supporting portion 21 of the frame 20, the two worm wheels 25 and 27 thus filling the space between the two portions 21 and 22. Driving worms 29 and 30 are provided for the worm wheels 25 and 27 respectively. The worm 30 is journaled in stationary bearings 31 and 32 carried by the frame 20, the arrangement for driving this worm and also the worm 29 being best shown in Fig. 13. As shown in 65 Fig. 13, the worm 30 is journaled for rotation in the bearings 31 and 32 and is provided with a longitudinal circular opening through which a shaft 33 extends. The shaft 33 is free to rotate relative to the worm 30 and carries a gear 34 rigidly secured to one end thereof. The gear 34 is provided with two sets of gear teeth, the set 35 as shown in Fig. 6 being arranged to mesh with the teeth of a gear 36 carried by the engine shaft. The teeth 37 mesh 70 with the pinion 38 rigidly secured to the end of the shaft 39, which carries the worm 29. A clutch 40 operated by a lever 40', is splined to the end of the worm 30 and is adapted to lock the gear 34 and the worm 30 to one another for rotation together. The end of the shaft 33 opposite the gear 34 is provided with a pinion 41 which meshes with the pinions 42 forming a part of a 75 system of planetary gearing best illustrated in Fig. 15. The outer gear 43 of the system is rotatably mounted on the end of the worm 30 and is provided with brake band 44 and lever 44' for holding it stationary 80 at the will of the operator. By this arrangement, the worm 30 may be driven directly by the gear 34 through the clutch 40, or it may be given a slower and more powerful movement through the planetary 85 gearing. When the clutch 40 is disconnected and the brake band 44 is loosened, the gear 35 will run free without driving the worm 30. The worm 29 is journaled in sliding bearings 45 which are movably 90 mounted on slideways 46 and which may be shifted back and forth to bring the worm 29 into and out of engagement with the worm wheel 25. The bearings 45 are shifted 95 by means of couplings 47 carried by eccentrics secured to the shaft 48, which extends transversely of the machine frame and which is provided with operating handles 49 located one at each side of the machine. The teeth of the gears 37 and 38 are of sufficient length that they permit of the shifting of worm 29 into and out of operative 100 engagement with the worm wheel 25 without breaking the connection between the gears 37 and 38. When the worm wheel 25 is rotated by means of the worm 29, it 105

110
 115
 120
 125
 130

will be raised or lowered by the threads on the supporting standard 1 and will carry with it the entire framework 20 with the mechanism mounted thereon. The framework will be normally locked from rotation relative to the standard 1 by the worm wheel 27 and the co-operating worm 30. When, however, it is desirable to rotate the frame and operating mechanism relative to the supporting standard, this may be done by driving the worm 30, which will thereby be fed around the periphery of the worm wheel 27, since this wheel is prevented from rotation on the standard by means of the key 28. The standard itself is prevented from rotating, as previously pointed out, by the construction of the head 16 and the arms 17 carried at the upper end of the standard.

The power mechanism for driving the mining machine is best illustrated in Figs. 6 and 10, and consists of a steam or compressed air reciprocating engine having two cylinders 50 and 51. The pistons of these cylinders operate cross heads 52 and 53 respectively, which are provided with guides 54 forming a part of the framework 20. The cross heads 52 and 53 are provided with connecting rods 55 and 56 respectively, which drive cranks 57 secured to the main shaft 58 of the engine. The shaft 58 carries the gear 36 for driving the two worms previously described, and also has loosely mounted thereon the sprocket wheel 59. A clutch 60 is slidably mounted on the shaft for securing the sprocket wheel 59 for rotation therewith. The clutch is operated by a rod 61 and a handle 62 located at the top of the framework and shown in Figs. 3 and 4. The shaft 58 also carries at each end thereof a pair of eccentrics 63 and 64 which operate the valves of the engine cylinders by means of eccentric rods 65 and 66 and reversing link mechanism 67 of well known construction. The reversing lever 68 is connected to the shaft 69, which extends transversely of the machine, as shown in Fig. 6, and which is connected to the link mechanism by a pair of arms 70 and 71. The energizing fluid is admitted to the cylinders of the engine through a pipe 72 and a flexible hose 73. A detachable connection 74 and a throttle valve 74' are provided between the hose 73 and the pipe 72. This connection, shown in detail in Fig. 16, is of well known construction and is provided with a valve 75 which automatically closes the supply hose 73 when the connection is broken. Guides 73' are provided to prevent mutilation of the hose 73 as the cutter head is rotated.

The base portion of the frame 20, upon which the operating parts just described are mounted, is extended as best shown in Fig. 3 to form a rotary table 76 having a

slidable extension 77 provided with an end stop flange 77' associated therewith. This table is in the form of a portion of a flattened ring partially surrounding the circular frame which carries the operating mechanism. At one edge formed by the discontinuation of this ring, a cutter frame 78 is provided, which is in the form of a loop having an unobstructed core-opening therethrough, as best shown in Fig. 5. The frame 78 is provided at its front edge with a sliding cutter chain 79 which meshes with the sprocket wheel 59 and is driven thereby. A projection 80 is provided at the upper portion of the frame 20 for directing the sprocket chain from the wheel 59 onto the frame 78. The chain 79 slides in guides on the frame 78 and is provided with bits 81 for cutting a kerf in the material to be mined.

Where the edges of the portions 76 and 77 of the swinging table meet, they are beveled as shown at 82 to overlap one another without forming an uneven surface on the top of the table. The extension 77, as shown in Fig. 7, has an overhanging lug 83 which rests upon a corresponding rim 84 extending outwardly from the periphery of the base portion of the framework 20. The extension 77 is also provided with arms 85 and 86 which partially encircle the cylindrical portion of the framework 20 and which are provided at their extremities with inwardly extending lugs 87 which fit within grooves or guideways 88 in the framework 20. By this construction the extension 77 is permitted to have a limited rotary movement about the axis of the cutter head by which it may be telescoped onto the portion 76 of the table, in order to bring the table into a smaller compass for a purpose which will be explained. To permit this folding or telescoping of the parts of the table, the extension 77 must be raised slightly, swinging about the diametrically disposed lugs 87, in order that it may occupy a position on top of the portion 76.

In operation, the machine is positioned in a mine chamber, as shown in Figs. 3, 4 and 5, and is secured in place by forcing the head of the standard 4 upwardly into contact with the roof of the chamber until the lugs 18 bite into the roof a sufficient distance to prevent rotation of the standard. The upper cut illustrated in Fig. 4 is preferably made first. The operating portion of the machine may be raised into this position by causing the engine to drive the worm 29 while it is held in mesh with the worm wheel 25 by means of the links 47 and hand cranks 49. During this operation, the worm 30 is disconnected from the engine and prevents rotation of the operating mechanism and its supporting frame about the standard 4, for the reason that the worm

wheel 27 is held from rotation on the standard by means of key 28, but is free to slide vertically thereon. When the operating parts of the machine are properly positioned vertically, the sprocket wheel 59 is clutched to the main shaft 58 and the cutter chain 79 is driven on the cutter frame 78. At the beginning of the operation, the cutter frame 78 is in such an angular position relative to the standard 4 that the cutting mechanism is properly located for beginning the cut illustrated in Fig. 3. After the chain 79 has been started, the worm 30 is driven by means of the planetary gearing connected therewith to slowly rotate the entire framework about the supporting standard in a counter clockwise direction, as viewed in Fig. 3. This feeds the cutter frame into the material to be mined in such a way as to sever a crescent-shaped portion from the face of the mine wall, as will be clear from an inspection of Fig. 3. At the beginning of the rotary movement of the machine, the table 76 will occupy such an angular position in the mine chamber that it may be necessary to have the extension 77 in its telescoped position to prevent its striking the wall of the mine on the side opposite that at which the cut is started. As the cutter frame is fed into the material, it will draw the table 76 into the bottom kerf formed by the chain cutter, and when the operation has proceeded a sufficient distance the extension 77 may be drawn away from the portion 76 so that the complete table, when extended, will be large enough to receive the entire section of material severed from the mine wall. As the material is cut from the wall, it may break into a number of pieces, depending upon the nature of the material being worked, but all of the material will be received and retained on top of the table 76. The material is prevented from contacting with the driving mechanism by means of an upstanding wall 89 which extends substantially around the periphery of the central portion of the machine and which supports a cover plate 90 resting on the top of the wall 89 and encasing the greater part of the operating mechanism. The wall 89 is provided with suitable dividing lines and detachable sections to permit proper assembling of the operating parts.

When a cut has been completed in the manner described, the brake band 44 is loosened to discontinue the rotation of the worm 30 by its planetary gearing, thus stopping the feeding movement of the cutter frame. The clutch 60 is also disconnected from the sprocket wheel 59 to discontinue the operation of the cutting chain 79. The clutch 40 is then operated to drive the worm 30 directly from the gear 35 in the same direction as that by which the cut was made and at a very much greater speed. This will cause the cutter head and the table 76 to be

swung in a counter clockwise direction as viewed in Fig. 3, and the table will carry with it the severed coal and bring it into a position in the rear of the cutter head, as shown in Fig. 4, from which it may be moved from the table into a car 91 or other suitable transporting mechanism. It will be apparent that by a complete operation, the cutter head will be rotated entirely around the supporting axis. If the operation were repeated a number of times, the supply hose 73 would be wound around the supporting standard. This is prevented, however, by disconnecting the hose after each cut and reconnecting it after it has been unwound from the standard. The engine, of course, could be reversed to rotate the cutter head in an opposite direction when the coal is swung into loading position, thus preventing the winding of the supply hose upon the standard. The preferable mode of operation is, however, to rotate the cutter head always in the same direction and to disconnect the hose after each cut is made.

After the upper cut has been completed, the machine is lowered on the standard and the lower cut is made in the same way as the upper one. After the lower cut has been completed, however, it will be necessary to drive the worm 29 to raise the machine and the severed coal into the upper position so that it may be discharged into the transporting car. The operation, of course, may be reversed and the lower cut taken first. If this is done it will be necessary to swing the table with the severed material thereon into position in the rear of the standard before it is raised into loading position. The machine may be operated in veins of any desired thickness, the number of cuts for each position of the machine depending upon the thickness of the vein. If the vein is a shallow one and can be completely removed by a single cut, an operating head like that shown in Figs. 10, 11 and 12 is used, the head being placed directly in the upper end of the supporting standard and a flat shallow pan being substituted for the car 91. If the vein is a thicker one, a sufficient number of extension members 7 is used in connection with the supporting standard to make the standard of the correct length to correspond to the height of the mine chamber.

In order to carry out the system of mining for which the machine described above is especially adapted, it is desirable to have an especially constructed mine support. Supports particularly adapted to this purpose are illustrated in Figs. 17, 18 and 21 to 25 inclusive. In Figs. 21 to 24 is shown a hydraulic mine support or prop especially designed for use in connection with the mining system constituting a part of this invention. This support is provided with a hollow base member 92 in which an operating

- fluid 93 is confined and in which an upper telescoping plunger 94 is mounted for a vertical sliding movement. The telescoping plunger 94 is provided at its lower end with 5 a piston 95, which makes a liquid-tight connection with the interior of the cylinder 92. The plunger 94 has an internal chamber 96, and the wall of this chamber is bored at 97 and 98 to form ducts for the passage of the 10 liquid to and from the two telescopic portions of the prop. The duct 98 extends downwardly through the piston head 95 and communicates with the chamber in the base 92. The duct 97 has an opening 99 through the wall 15 of the portion 94 into the chamber 96. A passage 98' connects the two ducts 98 and 97 near the lower end of the chamber 96 and a valve 98" is provided for opening and closing this passage, as is shown in Fig. 24. 20 The two ducts 97 and 98 are continued outwardly through the lug 100 at the upper end of the prop, where they are provided with nipples 101, best shown in Fig. 22, for connection with an operating pump. The nipple 25 connected with the duct 98 is provided with a one-way valve 102 for automatically closing the opening in the duct against outward pressure from the liquid 93 in the interior of the cylinder 92. A detachable 30 pump 103 shown diagrammatically is provided with a pair of hooks 104 by means of which it may be held in position adjacent the openings of the ducts 97, 98. The pump 103 is provided with a pair of projecting tubes 105 which make connection with the nipples 101 when the pump is in 35 operating position. The pump is driven by a motor 106 shown diagrammatically to the upper surface of which it is secured, and 40 which also drives a windlass 107 located at the base of the motor. Extending laterally from the upper and lower portions of the prop is a pair of arms 108 and 109. These arms are pivotally connected to the prop 45 at their inner ends and are provided with heavy springs 110 for forcing them away from one another. The amount of movement of the arms 108, 109 is very slight and is limited by inwardly projecting lugs 50 111, which fit over corresponding lugs 112 on the mine prop. There is a lug 111 on each side of the lug 112, and they are spaced apart sufficiently to permit of the slight movement of the arms 108, 109 which may be desirable. The arms 108 and 109 are in the form of plates extending laterally a distance somewhat greater than the diameter of the props themselves. The lower arm 109 is provided 55 at its extremities with a plurality of upwardly projecting lugs 113, there being a pair of these lugs located adjacent each lateral edge of the arm. The motor 106 is provided, as shown in Fig. 26, with a base member 114 having openings 115 there- 60 arranged to fit over the lugs 113 and hold the motor and its windlass in position on the arm 109, as illustrated in Fig. 18. At the inner end of the arm 109 is a boss 116, and the cable 117 carried by the windlass 107 is provided with a ring 118 arranged to fit over the boss 116, as is also shown in Fig. 18. The purpose of the windlass and cable is for moving the props relatively to one another in a way which 65 will be clear from this figure. Between the lugs 113 and the boss 116 and extending transversely of the arm 109, is a pair of upwardly projecting ribs 119 arranged to form a continuous track when a series of 70 props are placed side by side, as illustrated 75 in Fig. 2.
- In Fig. 25 is shown a modified form of mine prop, in which a standard 120 is mounted for vertical movement in an opening 121 in the base member 122. The standard 120 has an internal chamber 123 and is provided with a piston head 124 fitting within the chamber 121. A passage 125, extending through the piston head 124, connects the chambers 121 and 123. The passage 125 may be opened and closed by means of a valve 126 to permit the flow of liquid from one chamber to the other. The standard 120 is provided with a flange 127 which rests upon a heavy coil spring 128 supported by the upper portion of the base 122. A cap 129 has a screw-threaded connection with the upper portion of the base 122 and an inwardly projecting flange 130, which bears against the upper surface of the 80 flange 127 on the standard 120. 85
- The upper end of the standard 120 is provided with screw threads 131, on which a bevel gear 132 is threaded. The head 133 of the mine prop telescopes over the threaded portion of the standard and is provided with openings 134, by means of which a detachable hand wheel 135 may be held in 90 position to cause a pinion 136 to mesh with the gear 132 to rotate the gear 132 on the standard 120. 95
- The base 122 is provided with a laterally projecting arm 137 which is similar to the arm 109 of the prop previously described, 100 with the exception that it is made rigid with the base of the prop instead of being pivoted thereto. The head 133 is also provided with a laterally projecting arm 138 which is rigid with the head and which is provided with an offset portion 139, leaving the upper end of the head proper a little higher than the upper surface of the laterally projecting arm. 110
- When a prop of this form is placed in 115 position in a mine chamber, the head is forced upwardly into contact with the roof of the mine by means of the hand wheel 135. The standard 120 is prevented from settling in the base 122 by the liquid in the chamber 121, the valve 126 being closed. 120
- 125
- 130

After a prop of this character has remained for some time in a mine chamber, the operating parts become set and difficult to move. Therefore, when it is desirable to remove the prop, instead of operating the hand wheel 135 the valve 126 is opened, and the weight on the head of the prop forces the standard 120 downwardly against the resistance of the spring 128, the liquid in the chamber 121 flowing through the passage 125 into the chamber 123. As soon as the strain upon the screw threads 131 is thus released, the bevel gear 132 may be easily operated to further lower the head of the prop. As the head is lowered, the spring 128 will again expand and the liquid will return to the chamber 121, after which the valve 126 may again be closed so that the prop will be in condition for a second operation. A similar result is accomplished in connection with the prop shown in Fig. 21, by opening the valve 98" and permitting the liquid to flow through the duct 98' from the lower portion to the upper portion of the prop.

The operation of the mining system for which the above described mechanism is especially adapted will best be understood by Figs. 1, 2 and 17 to 20 inclusive. A shaft *a* is first sunk from the surface of the earth to a level with the vein of coal which is to be mined. The mechanism and system are especially applicable to deep mines where the pressure is very great, but they may be used for mining coal at any depth. From the shaft *a*, entries *b* are made through the vein of coal to any desired distance from the shaft, the length of the entries depending upon the conditions of the particular field being operated. A pillar *c* is left between the entries to separate the two in order to provide for better ventilation. The machine shown in Figs. 4 and 5 is used in driving the entries, the width of the entry being determined by the width of the cut made by the machine. As the entry is driven forward, props like those shown in Figs. 21 and 25 are placed by the side of the entry with the arms extending across the floor and the roof forming a lining for both the floor and the roof of the entry. The position of the props in the entry may be understood by reference to Fig. 17.

The ribs 119 on the bottom arms 109 form a track over which cars may be run behind the machine as it progresses to carry away the excavated material. Practically all the weight of the earth above the entry is borne by the head of the prop, the laterally extending arms 108 being merely for the purpose of preventing dropping of loose portions from the roof of the mine. The coil springs which force the arms 108 upwardly will permit the arms to move a sufficient amount to compensate for any unevenness in the roof of the mine chamber and prevent

undue pressure upon the arms. After the entries *b* have been driven a sufficient distance, if it is found desirable the props may be removed and permanent timbering and tracks substituted. From the main entries *b*, laterals *d* and *e* are driven to any desired distance from the main entries, and other entries *f* are run parallel with the main entries *b* for the purpose of facilitating the mining operation. When this much has been accomplished, a number of machines *g* are operated in conjunction with one another to completely remove the material from the vein. The procedure by which the material is removed will best be understood by referring to Fig. 2. The entries parallel with the main entries *f* *b* in the preferred method of operation, are only the width of a single cut made by one of the machines. They may be made of greater width, however, in order to accommodate a double track, as is shown at *f* Fig. 2. Two machines *g* are set to operate simultaneously from alternate entries *f*, and may be moved after each cut by air cylinders *n*. As the machines progress across the face of the portions of the vein between the entries, props are placed behind the machines and contiguous to one another to form tracks upon which the cars for removing the material are run. The machines will be operated back and forth across the face of the vein, each movement of the machine across the face of the portion of the vein between the entries removing a section of the vein of a width equal to that of a cut made by the machine and contiguous to the space left by the next preceding cut. As the machines are moved along the face of the vein, the props will be successively drawn from their previous position into a position directly behind the operating machine. This is done in the manner illustrated in Fig. 18 by means of the motor 106 and windlass 107. As the props are drawn to their new positions, the roof of the mine from which they are removed is left unsupported and is free to fall into the space from which the coal has been removed. It should be noted that the nature of the mining machine especially adapts it to this method of operation, since the machine has no front or rear but may operate in any direction found desirable. In driving entries, the machine may work in one direction until an entry of sufficient length has been made, and then it may continue to operate to drive an entry at right angles to the one already formed, without any turning of the machine whatever. In this way the machine may be turned from one direction to another, in the space made by its own cut.

The track used in the entries *f* is made in sections *h* of a length equal to the width of the cut made by one of the machines. After each section of material is removed from the

face of the vein, a section *h* of the track is taken up and the switching section *i* of the track is moved to a new position in the entry to correspond to the new position of the machine. If desired, one or more machines *j* may be kept in operation driving the various entries used in connection with this system of mining. This is not essential, however, and the entries may be driven as needed by the machines used for removing the bulk of the material. Any number of batteries of mining machines may be operated at one time in the mine, the second battery being shown at *k*, in Fig. 1. As a battery works inwardly toward the main shaft, the roof of the mine being left unsupported will fall and fill the space from which the coal has been removed.

Since the coal is removed right up to the mine entries *b*, the roof in falling will have a tendency to break down the roof of these entries. To prevent this, it may sometimes be desirable to form a kerf in the rock above and at the edge of the entry *b*, as illustrated in Fig. 19. This may be done by means of a machine *l* of well known construction. After such a kerf has been formed, the coal *m* at the side of the entry may be removed and the earth above this coal in falling will not then draw down with it the roof of the entry but will fall as illustrated in Fig. 20 preserving the entry for any further use that may be desired of it.

The props used in connection with the machine are of heavy construction and are especially designed for use where the pressure of the earth is very great. In consequence of this, they are of course rather expensive to manufacture. But, by using them in conjunction with the machine described, the cost of timbering in a mine is greatly reduced. This is due to the fact that the mining operation is concentrated in a small area and only a comparatively small number of props is necessary to produce a given output from the mine. The props, of course, are used over and over again for a period covering a number of years, and thus although the first cost of the props is considerable, a great saving is accomplished in the ultimate cost of timbering, which is becoming more and more expensive as the cost of timber advances. By the use of the machine and process described, the entire vein of coal is removed from the mine without the necessity of leaving pillars or timbers in the mine after working is completed, and the dangers from insecure timbering and mining operations extending over a large area in order to produce a required output, are practically eliminated.

In my divisional application, Serial No. 587,188, filed September 9, 1922, for an improvement in roof-supporting mechanism for coal mines, I have described and claimed

the system of mining and loading illustrated in Figs. 1 and 2 of the accompanying drawings and also the specific form of roof supports illustrated in Figs. 17 and 18, and Figs. 21 to 27, inclusive.

70

I claim:

1. In a mining machine, the combination with a frame having a supporting standard, of a supplemental frame carried by said standard and rotatable freely about the same, kerf-cutting mechanism comprising a cutter chain mounted on said supplemental frame to move bodily therewith, power mechanism on said supplemental frame for driving said cutter chain, power mechanism on said supplemental frame for moving the latter together with said kerf-cutting mechanism in an arc about said standard to effect arcuate feed of said kerf-cutting mechanism, and power mechanism on said supplemental frame for adjusting the elevation of said supplemental frame together with said kerf-cutting mechanism on said standard.

120

3. In a mining machine, the combination with a roof jack to constitute a supporting frame, of cutting apparatus mounted on said roof jack intermediate its ends for a complete rotation about said jack, means for operating said cutting apparatus including feed thereof along an arc on said roof jack as an axis, and self-acting power mechanism for adjusting the height of said cutting apparatus comprising means for moving the cutting apparatus rectilinearly along said jack.

115

120

125

4. In a mining machine, the combination with supporting framework, of core-cutting apparatus mounted thereon and having an upper run for cutting a kerf in an approximately horizontal plane, and a lower run for cutting a kerf in an approximately horizontal plane spaced from said first-named kerf, means for operating said core-cutting apparatus including feeding movement there-

of, and means for adjusting the height of said core-cutting apparatus in its entirety by rectilinear vertical movement thereof relatively to said supporting framework to secure a plurality of cuts across a mine wall including an approximately horizontal kerf cut at the ceiling of the mine chamber and an approximately horizontal kerf cut at the floor of the mine chamber.

10 5. In a mining machine, the combination with a main frame, of a supplemental frame completely rotatable about a central upright axis on said main frame, a platform on said supplemental frame, core-cutting mechanism having an unobstructed core-opening therethrough for the passage of a core onto said platform, and means for operating said core-cutting mechanism including arcuate feed thereof on said central upright axis to 20 cut a core of material from a mine wall in position to be received by said platform.

6. In a mining machine, the combination with a supporting frame comprising an upright standard, of means for securing said standard in a mine chamber, a rotary frame 25 mounted on said standard, kerf-cutting mechanism mounted on said rotary frame and movable bodily therewith, means for adjusting said rotary frame and said kerf-cutting mechanism rectilinearly along said standard, and self-acting power mechanism for operating said kerf-cutting mechanism including arcuate feed thereof about said standard as an axis.

35 7. In a mining machine, the combination with a supporting standard, of means for varying the length of said standard, means for securing said standard in an upright position in a mine chamber, a rotary frame 40 mounted on said standard, kerf-cutting mechanism mounted on said rotary frame in fixed relation thereto and for bodily movement therewith, means for adjusting said rotary frame and said cutting mechanism 45 vertically and rectilinearly relatively to said standard, and means for operating said kerf-cutting mechanism including arcuate feed thereof about said standard as an axis.

8. In a mining machine, the combination 50 with a base frame having an upright standard, of a supplemental frame mounted to rotate about said standard in substantially horizontal planes, kerf-cutting mechanism mounted on said supplemental frame to move bodily therewith, means on said supplemental frame for adjusting the position of the latter together with said kerf-cutting mechanism rectilinearly along said standard, and self-acting power mechanism for operating 55 said kerf-cutting mechanism including arcuate feed thereof about said standard as an axis and along horizontal planes.

9. In a mining machine, the combination 60 with a base frame adapted to rest on the floor 65 of a mine chamber, of an upright standard

on said base frame, an upward extension detachably mounted on said standard and held against rotation relatively to said standard, a roof-engaging device extending upwardly from said extension, means 70 for forcing said roof-engaging device against the roof of the mine chamber to anchor said base frame, said standard and said upper extension firmly in position between the floor and roof of the mine chamber 75 and hold said standard and said upper extension against angular rotation, a supplemental frame adapted to be supported by said standard or by said upper extension, cutting mechanism carried by said supplemental 80 frame, and means for completely rotating said supplemental frame together with said cutting mechanism about said standard or about the upper extension thereof at a predetermined elevation and along horizontal 85 planes.

10. In a mining machine, the combination with a supporting standard, of means for securing said standard in an upright position in a mine chamber, a rotary frame 90 mounted on said standard for movement longitudinally thereof and for rotation about the same, threads on said standard, a nut meshing with the threads on said standard, mechanism on said rotary frame for rotating said nut to move said rotary frame rectilinearly along said standard, kerf-cutting mechanism mounted on said rotary frame and movable bodily therewith, a gear splined 95 to said standard to slide along the same longitudinally, self-acting power mechanism on said rotary frame connected to said gear to effect rotary feed of said cutting mechanism in horizontal planes about said standard as an axis, and means on said rotary 100 frame for driving said cutting mechanism.

11. In a mining machine, the combination with a supporting standard, of threads on said standard, a rotary frame on said standard, kerf-cutting mechanism on said rotary frame for movement bodily therewith, means on said frame for driving said cutting mechanism, a nut on said standard, self-acting power mechanism on said frame 110 for rotating said nut to move the frame along said standard, means between said standard and said frame to confine such movement along said standard to rectilinear movement parallel to the axis of said standard, and means for rotating said frame and said cutting mechanism about said standard to feed the cutting mechanism arcuately in planes perpendicular to the axis of said standard.

12. In a mining machine, the combination 115 with a supporting standard, of a frame supported by said standard, cutting mechanism mounted on said frame, means for operating said cutting mechanism, a nut threaded on said standard, self-acting power mechanism 120

for rotating said nut to secure adjustment of said frame and said cutting mechanism along said standard, and mechanism between said standard and said frame for preventing relative rotation and compelling said frame and said cutting mechanism to move rectilinearly when adjusted along said standard.

13. In a mining machine, the combination with a supporting standard, of means for anchoring said standard free from obstructions in horizontal planes between the ends of said standard, a supplemental frame mounted for rotary movement in horizontal planes about said standard and for adjustment to various elevations longitudinally of said standard, a worm wheel mounted on said supplemental frame and threaded onto said standard, an additional worm wheel mounted on said supplemental frame and splined to said standard to limit the movement of said additional worm wheel to a path longitudinally of said standard, means for actuating said first-named worm wheel to adjust the height of said supplemental frame along said standard, mechanism engaging said additional worm wheel for rotating said supplemental frame at adjusted elevation about said standard, core-cutting mechanism mounted on said supplemental frame and movable bodily therewith, and mechanism mounted on said supplemental frame for actuating said core-cutting mechanism while being fed in an arc by said means for rotating said supplemental frame about said standard.

14. In a mining machine, the combination with a main frame having a threaded extension, of a supplemental frame rotatable about said threaded extension and comprising spaced-apart ring bearings adjacent said extension, two worm wheels on said extension between said ring bearings of said supplemental frame, one of said worm wheels being threaded to said extension and the other being splined longitudinally thereof, means connected to the splined worm wheel for moving said supplemental frame in an arc relatively to said main frame, cutting apparatus mounted on said supplemental frame and movable bodily therewith, means for actuating said cutting apparatus while being fed in an arc by arcuate movement of said supplemental frame relatively to said main frame, and mechanism for rotating the worm wheel threaded onto said standard to effect adjustment of said cutting apparatus along said extension.

15. In a mining machine, a standard, means for securing said standard in an upright position in a mine chamber, a cutter head mounted on said standard, a nut carried by said cutter head and threaded on said standard, gearing carried by said cutter head for rotating said nut to move said cutter head rectilinearly and longitudinally

of said standard, and mechanism for locking said cutter head against rotation on said standard during the rotation of said nut.

16. In a mining machine, the combination with a supporting frame having a threaded portion, of a supplemental frame mounted on said threaded portion for movement longitudinally thereof and for rotation angularly thereabout, cutting apparatus mounted on said supplemental frame and movable bodily therewith, a pair of gears on said threaded portion, one threaded to said threaded portion and the other slidable longitudinally thereof while confined against rotary movement relatively thereto, means for rotating the threaded gear to effect rectilinear movement of said supplemental frame and cutting apparatus relatively to said supporting frame, and means for driving said cutting apparatus, and means for engaging the other gear to move the supplemental frame and the cutting apparatus around the threaded portion of said supporting frame to secure arcuate feeding movement of said cutting apparatus. 90

17. In a mining machine, the combination with a main frame having a threaded extension, of a supplemental frame having spaced-apart rings surrounding said extension, a pair of worm gears between said rings, one threaded to said extension and the other splined longitudinally thereof, kerf-cutting mechanism mounted on said supplemental frame, means for actuating said kerf-cutting mechanism, mechanism connected to said splined worm gear for moving said supplemental frame in an arc relatively to said main frame to effect arcuate feed of said kerf-cutting mechanism, and mechanism connected to the threaded worm gear for adjusting the supplemental frame relatively to said main frame to vary the position of said kerf-cutting mechanism. 95

18. In a mining machine, the combination with a supporting frame having an upright threaded standard, of means for securing said standard in an upright position in a mine chamber, a supplemental frame mounted on said standard for movement around the same and longitudinally thereof, cutting mechanism mounted on said supplemental frame for movement bodily therewith, a worm gear mounted on said standard to slide longitudinally thereof and splined to said standard to prevent rotation relatively to said standard, means for engaging said worm gear to swing said supplemental frame and said cutting mechanism about said standard in horizontal planes, a gear threaded to said standard, means for engaging said threaded gear to move the supplemental frame and the cutting mechanism rectilinearly and vertically along said standard while confined against rotation relatively to said standard by said first-named worm gear and its en- 110 115 120 125

gaging mechanism, and means for driving said cutting mechanism during arcuate movement thereof in such horizontal planes.

19. In a mining machine, the combination 5 with a supporting standard, of means for anchoring said standard in an upright position in a mine chamber, core-cutting mechanism having an unobstructed core-opening therethrough and mounted for 10 arcuate movement about said standard, a platform movable bodily with said core-cutting mechanism in position to receive material from the core, and means for operating said core-cutting mechanism including 15 arcuate feed thereof about said upright standard and arcuate movement of said platform under the core of material while being cut.

20. In a mining machine, the combination 20 with a supporting frame, of means for anchoring said frame in a mine chamber, a supplemental frame mounted for vertical adjustment on said supporting frame, cutting apparatus mounted on said supplemental frame for arcuate movement with the latter on said supporting frame, means for operating said cutting apparatus including arcuate movement thereof on said supporting frame, means comprising a motor carried by said 25 supplemental frame for moving the latter and said cutting apparatus rectilinearly to adjust the elevation of said cutting apparatus relatively to said supporting frame, and mechanism for locking said supplemental frame against rotary movement during such rectilinear adjustment.

21. In a mining machine, a supporting standard, means for securing said standard in an upright position in a mine chamber, a 40 cutter head mounted on said standard and adjustable longitudinally thereof and angularly thereabout, a motor carried by said cutter head, and gearing driven by said motor for causing said cutter head to move 45 longitudinally of said standard and angularly thereabout at the will of the operator.

22. In a mining machine, the combination 50 with a roof jack comprising a plurality of sections detachably connected together in series in alignment on a common axis, of a supplemental frame mounted on said roof jack, cutting mechanism mounted on said supplemental frame to move bodily therewith, power mechanism for moving said 55 supplemental frame together with said cutting mechanism rectilinearly along lines parallel to said axis, and self-acting power mechanism mounted on said supplemental frame for operating said cutting mechanism 60 including arcuate feeding movement thereof in planes substantially perpendicular to said axis.

23. In a mining machine, the combination 65 with a supporting standard, of means for securing said standard in an upright position

in a mine chamber, a supplemental frame movable about said standard and longitudinally thereof, cutting mechanism mounted on said supplemental frame to move bodily therewith, means on said supplemental frame 70 for driving said cutting mechanism, self-acting power mechanism on said supplemental frame and engaging said standard for automatically and continuously rotating said cutting mechanism about said standard 75 in the same direction and in the same planes, and additional self-acting power mechanism on said supplemental frame and comprising a gear threaded to said standard for adjusting the elevation of said cutting mechanism 80 by movement of said supplemental frame longitudinally of said standard.

24. In a mining machine, the combination with a main frame having an upright threaded post extending therefrom, of a 85 supplemental frame having spaced-apart rings slidable along said threaded post, a pair of worm gear wheels between said rings, one threaded to said post and the other splined for movement longitudinally thereof, kerf-cutting mechanism mounted on said supplemental frame and movable bodily therewith, means for actuating said kerf-cutting mechanism, power mechanism mounted on said supplemental frame and 90 connected to the splined worm gear wheel for automatically moving said supplemental frame in an arc about said post to effect feeding movement of said kerf-cutting mechanism, and power mechanism connected to said threaded worm gear wheel for automatically adjusting the elevation of said supplemental frame and said kerf-cutting mechanism rectilinearly along said post.

25. In a mining machine, the combination 100 with a main frame, of a supplemental frame rotatable about a predetermined axis on said main frame, a kerf-cutting mechanism comprising a cutter chain mounted on said supplemental frame and movable bodily therewith, self-acting power mechanism on said supplemental frame for driving said kerf-cutting mechanism, means for rotating said supplemental frame together with said kerf-cutting mechanism about said axis in the 105 same direction a number of times while said axis remains in fixed relation to said main frame, and self-acting power mechanism mounted on said supplemental frame for moving the latter and said kerf-cutting mechanism along said axis to a new cutting position during the rearward swing of the cutting mechanism from the mine wall back to the mine wall.

26. In a mining machine, the combination 115 with a main supporting frame, of means for anchoring said frame in an upright position in a mine chamber, a supplemental frame mounted for vertical adjustment on said main frame, core-cutting mechanism 120

- having an unobstructed core-opening therethrough and mounted on said supplemental frame for upright rectilinear movement therewith, means comprising a drive shaft 6 and a reciprocating engine connected thereto for operating said core-cutting mechanism including arcuate feed thereof about an upright axis on said main frame, and means operated by said reciprocating engine for moving said supplemental frame and said core-cutting mechanism rectilinearly in an upright direction to adjust the elevation of said core-cutting mechanism relatively to said main frame.
- 15 27. In a mining machine, a supporting standard, means for securing said standard in an upright position in a mine chamber, a cutter head mounted on said standard comprising a platform and a loop cutter, 20 gearing carried by said platform for operating said loop cutter, gearing carried by said platform for independently adjusting said cutter vertically and angularly on said standard, and a motor mounted on said platform for driving said gearing.
- 25 28. In a mining machine, the combination with a supporting standard, of means for securing said standard in an upright position in a mine chamber, a supplemental frame rotatable about said standard and movable longitudinally thereof, a motor carried by said supplemental frame, cutting mechanism carried by said supplemental frame and movable bodily therewith, power 30 mechanism driven by said motor and comprising locking worm gearing connected to said standard for rotating said supplemental frame together with said cutting mechanism about said standard in substantially horizontal planes and entirely about said standard, and mechanism driven by said motor and comprising a gear threaded to said standard for moving said supplemental frame and said cutting mechanism 35 rectilinearly along said standard while said locking worm gearing prevents rotation of said supplemental frame and said cutting mechanism about said standard.
- 40 29. In a mining machine, the combination with a supporting frame, of a supplemental frame rotatably mounted on said supporting frame, cutting apparatus mounted on said supplemental frame to move bodily therewith, means for driving said cutting apparatus, and means comprising brake-mechanism for moving said supplemental frame and said cutting apparatus to effect arcuate feed of said cutting apparatus, said feeding movement being controlled by the extent of application of said brake-mechanism.
- 45 30. In a mining machine, the combination with a main frame, of a supplemental frame, cutting apparatus mounted on said supplemental frame, means comprising a worm with a shaft extending loosely
- through the same for moving said supplemental frame relatively to said main frame to effect feeding movement of said cutting apparatus, means for actuating said cutting apparatus during such feeding movement, 7 and means associated with said shaft for varying the speed of movement of said worm to effect different rates of feeding movement of said cutting apparatus.
31. In a mining machine, the combination with a main frame, of a supplemental frame rotatably mounted on said main frame, cutting apparatus mounted on said supplemental frame, means comprising a shaft for moving said supplemental frame in an arc relatively to said main frame to effect arcuate feeding movement of said cutting apparatus, means for actuating said cutting apparatus during such feeding movement, and mechanism associated with the ends of said shaft for varying the speed of feeding movement of said cutting apparatus.
32. In a mining machine, a standard, cutting apparatus mounted for rotation about said standard, a worm for rotating said cutting apparatus about said standard to feed said cutting apparatus, spur gearing for driving said worm at one speed, planetary gearing for driving said worm at a different speed, and means for selectively connecting said worm with said gearing at the will of the operator to vary the rate of feeding said cutting apparatus.
33. In a mining machine, the combination with a supporting frame, of a supplemental frame mounted on said supporting frame for complete rotation about the same, cutting mechanism carried by said supplemental frame and movable bodily therewith, means for driving said cutting mechanism, means for rotating said supplemental frame on said supporting frame to effect arcuate feed of said cutting mechanism, and a plane table on said supplemental frame movable with said cutting mechanism in position to receive the material severed by said cutting mechanism.
34. In a mining machine, the combination with a main frame, of a supplemental frame mounted on said main frame for rotation about an upright axis through a complete circle, cutting machine mounted on said supplemental frame and movable therewith about said upright axis to dislodge material from a mine wall, and a table following in the path of said cutting mechanism to receive the dislodged material and carry the same arcuately back from the mine wall.
35. In a mining and loading machine, the combination with a main frame, of a mining machine bodily movable on an upright axis on said main frame, said mining machine comprising a loop chain core-cutter having an unobstructed core-opening therethrough, and means for operating said core- 1

cutter including arcuate feed thereof by arcuate movement of the entire mining machine about said upright axis on said main frame, and a table mounted on said mining machine in position to receive the core and carry the same intact or in a large blocks toward loading position.

36. In a mining machine, a cutter head rotatable about an upright axis, and a table secured to said cutter head for receiving the material severed thereby, said table having an adjustable extension movable into a retracted position to prevent said table from interfering with the operation of said cutter head.

37. In a mining machine, a cutter head rotatable about an upright axis, and an arcuate table extending radially from said cutter head to receive the material severed thereby and provided with an extension for adjusting said table to vary the angular expanse of said table about said cutter head.

38. In a mining and loading machine, the combination with a mining machine comprising a cutter for severing material from a mine wall, of a supporting frame for said mining machine, and a collapsible table secured to said mining machine to receive the material severed thereby, said table being arranged to telescope upon itself when one end thereof abuts against the mine wall to permit proper positioning of said cutter at the beginning of a cutting operation and arranged to be extended to receive the material severed by said cutter.

39. In a mining and loading machine, the combination with a main frame, of a supplemental frame mounted on said main frame for rotation on an upright axis, a mining machine mounted on said supplemental frame and comprising operating means including mechanism for feeding said mining machine in an arc on an upright axis through any angle relatively to said upright axis whereby said main frame may be advanced in any desired direction from a given position in a mine chamber, and means on said supplemental frame and movable bodily therewith in position for receiving the dislodged material directly from said mining machine and transferring such dislodged material from its severed position to a position for loading.

40. In a mining machine, the combination with a supporting frame, of a supplemental frame mounted on said supporting frame, loop chain core-cutting mechanism having an unobstructed core-opening therethrough and mounted on said supplemental frame in position to cut material from an upright mine wall at any side of said supporting frame, thereby permitting the mining machine to be advanced in any direction desired from a given location within the mine chamber being formed by said machine,

means for operating said core-cutting mechanism including feeding movements thereof relatively to said supporting frame, and means in position for receiving severed material from said core-cutting mechanism in any of the operating positions of the latter and transferring the received material to a position for loading.

41. In a mining and loading machine, the combination with a supporting frame movable in any direction at will from a given position in a mine chamber, of a mining machine comprising kerf-cutting mechanism operable to sever material in advance of said supporting frame in any direction in which said supporting frame may be moved, said mining machine comprising means for operating said kerf-cutting mechanism including arcuate feed thereof through any angle relatively to said supporting frame, and loading mechanism also carried by said supporting frame for receiving the severed material directly from its original position in the mine wall and transferring such material toward loading position.

42. In combination, a supporting standard, a cutter head secured to said standard and rotatable thereon for severing material to be mined, an arcuate member secured to said cutter head and forming a table to receive the severed material, and means for moving said cutter head and table vertically on said standard to raise the severed material into position to be loaded.

43. In combination, a mining machine, an upright standard, a cutter head mounted on said standard and rotatable thereon to sever material to be mined, an arcuate member secured to said cutter head and forming a table to receive the material severed thereby, and means for moving said cutter head and table vertically on said standard and for rotating said cutter head and table about said standard to bring the material on said table into position to be loaded.

44. In mining apparatus, the combination with a mining machine, of an upright exteriorly threaded standard on which said mining machine is adjustably mounted, a detachable exteriorly threaded extension on top of said standard to form a continuation of said threaded standard for supporting said mining machine at higher elevations than said standard, and means on top of said extension in position to engage the roof of a mine chamber for holding the standard and said extension in stationary position during the operation of said mining machine in adjusted position on said standard or on said extension, said engaging means being capable of being retracted to permit the removal of said detachable extension from said standard while said mining machine is supported by the latter.

45. In combination, a mining machine, a standard on which said mining machine is mounted, a detachable extension for said standard having slots at the upper end thereof, and a head fitted within said extension and having laterally extending arms arranged to contact with the roof of the mine to prevent rotary movement of said standard, said arms being movable into said slots to permit longitudinal movement of said head relative to said extension.
46. In a mining and loading machine, the combination with a supporting frame, of a mining machine mounted on said frame for movement successively across the face of a vein of material to be mined and operable to sever material in advance of said supporting frame independently of the direction in which it is moved to a new location, and means additional to said mining machine and also carried by said supporting frame for transferring the severed material from its cut position in the mine wall to a position in the rear of said supporting frame regardless of the direction in which said supporting frame is moved to a new location.
47. In a mining and loading machine, the combination with cutting mechanism, of supporting frame work therefor, means for operating said cutting mechanism including feeding movement thereof over a portion of a complete rotation, means for receiving the severed material, and connections between said receiving means and said cutting mechanism whereby continued rotation of the latter effects the transfer of the severed material on said receiving means toward loading position.
48. In a mining and loading machine, the combination with a mining machine mounted for continuous rotation in the same direction about an upright axis and comprising cutting mechanism and means for operating the same including arcuate feed thereof about such upright axis, loading mechanism connected to said mining machine to follow said cutting mechanism to receive the material severed thereby and carry the same toward loading position, a motor carried by said mining machine and movable bodily therewith about said upright axis, and a conduit detachably secured to said mining machine for supplying an energizing medium to said motor.
49. In a mining machine, the combination with a supporting frame, of core-cutting mechanism having an unobstructed core-opening therethrough and mounted on said supporting frame in position to cut a core of material in its native bed in substantially horizontal planes including a substantially horizontal plane at the floor of the mine chamber, means for driving said cutting mechanism, means for feeding said cutting
- mechanism to cut such a core in substantially horizontal planes in one operation, and means for shifting the cutting mechanism to a higher elevation relative to said supporting frame in position to cut another core of material in one operation in vertical alinement with the floor core and to effect a cut at the roof of the mine chamber in a substantially horizontal plane.
50. In a mining machine, the combination with a supporting frame, of a loop chain core-cutter having an unobstructed core-opening therethrough and mounted on said frame for vertical adjustment thereon in position to cut cores in vertical alinement with each other, means for driving said loop chain core-cutter, means for feeding said cutter with its lower length in a predetermined plane, means for shifting said cutter in its entirety along said supporting frame to a higher position to cut a core in vertical alinement with the lower core and the upper length of the cutter moving in a plane parallel to the first-mentioned plane and the lower length of the cutter moving along a path above said first-mentioned plane.
51. In a mining machine, the combination with a loop chain core cutter having an unobstructed core opening therethru, of means for actuating said cutter, means for feeding said cutter to effect a cut of the lower length of the cutter along the floor of the mine chamber, and means for elevating the position of said cutter as a whole to cut a core directly above the lower core and with the cut along the roof of the mine chamber substantially parallel with the floor cut and with the lower length of the cutter moving along a path above the said floor.
52. In a mining machine, the combination with a supporting frame, of a supplemental frame mounted on said supporting frame, cutting mechanism carried by said supplemental frame, a motor carried by said supplemental frame, means operated by said motor for moving said supplemental frame and said cutting mechanism rectilinearly longitudinally of said supporting frame to adjust the position of said cutting mechanism relatively to said supporting frame, and means driven by said motor for operating said cutting mechanism including angular movement of said supplemental frame about said supporting frame to effect arcuate feeding movement of said cutting mechanism.
53. In a mining machine, the combination with a supporting standard, of a supplemental frame mounted on said standard, core-cutting mechanism carried by said supplemental frame and having an unobstructed core-opening therethrough, gearing carried by said supplemental frame for independently adjusting said core-cutting mechanism vertically and angularly on said

standard, and a motor mounted on said supplemental frame for driving said gearing.

54. In a mining machine, the combination with a supporting frame, of core-cutting mechanism mounted thereon for arcuate movement about an upright axis, means for operating said core-cutting mechanism including arcuate feeding movement thereof about such axis, and an arcuate table supported by said frame in position to receive the material of the core directly from the core-cutting mechanism, said table comprising an extension for adjusting said table to vary the angular expanse thereof back of said core-cutting mechanism.

55. In a loading machine, the combination with supporting framework, of an arcuate platform mounted on said framework and movable up and down rectilinearly relatively to said framework, means for adjusting the elevation of said platform rectilinearly relatively to said framework while maintaining said platform in a substantially horizontal plane, and means for operating said platform arcuately relatively to said framework in a general horizontal direction to effect the transfer toward loading position of a block of material bounded at the bottom, top and sides by kerfs while in its native bed.

56. In a loading machine, the combination with a screw-threaded roof jack, of an arcuate table rotatably and longitudinally mounted on said roof jack, means for moving said arcuate table rectilinearly and longitudinally of said roof jack to adjust the elevation of said table, and means for moving said table arcuately into a horizontal kerf in a mine wall to receive material dislodged above said kerf and carry such material toward loading position.

57. In loading apparatus, the combination with a supporting frame having a screw-threaded portion, of a carrier mounted thereon, means engaging said screw-threaded portion for adjusting the elevation of said carrier on said supporting frame, and means for operating said carrier at any of its adjusted elevations to take the load of material directly from its native position in a mine wall and carrying the same toward loading position.

58. In loading apparatus, the combination with a supporting frame having an upright standard, of a carrier mounted on said frame for arcuate movement on the upright axis of said standard, self-acting power mechanism connected between said carrier and said standard for moving said carrier rectilinearly and vertically to adjust the elevation of said carrier while maintaining it in substantially horizontal position, and means for operating said carrier to take a load of material directly from its native position in a mine wall and moving said carrier together

with the material thereon in a general horizontal direction substantially in the plane of said carrier when the latter has received its load.

59. In a mining machine, the combination with a supporting frame, of core-cutting mechanism mounted thereon and including a guiding frame having an unobstructed core-opening therethrough and upper and lower runs rectilinear in elevation with the space between them less than the longitudinal length of said cutter frame projecting forwardly from said supporting frame, means for adjusting the elevation of the entire cutter frame rectilinearly to predetermine the elevation of the core to be cut from the mine wall between the floor and roof of a mine chamber, and means for operating said core-cutting mechanism in any of its adjusted positions including the feed thereof in a direction transverse to the actuating path to cut upper and lower substantially flat surfaces and a core projecting through said unobstructed core-opening of said cutter frame.

60. In a mining and loading machine, the combination with a main frame, of a supplemental frame mounted on said main frame for movement relatively thereto, an extensible platform mounted on said supplemental frame and comprising relatively movable sections, means for adjusting the elevation of said supplemental frame to effect the adjustment of the elevation of said platform with the forward section in receiving position ahead of the rear section at various elevations adjacent a mine wall between the floor and roof of the mine chamber, and means for moving said supplemental frame relatively to said main frame to cause said platform to carry material from the mine wall toward loading position.

61. In a mining and loading machine, the combination with a main frame, of a supplemental frame mounted on said main frame for arcuate movement on an upright axis, core-cutting mechanism mounted on said supplemental frame for arcuate movement therewith on such upright axis, an arcuate platform rigidly connected to said supplemental frame and extending back from said core-cutting mechanism in position to receive the core cut thereby, of means for operating said core-cutting mechanism including arcuate feeding movement thereof by movement of said supplemental frame in an arc on said upright axis and while said arcuate platform is moved under the core being produced by said core-cutting mechanism, an arcuate extension for said platform, and means for supporting said extension on said supplemental frame to permit said extension to be collapsed relatively to said arcuate platform when said arcuate platform and its extension are reversed to carry

the core of material back from the mine wall and said extension abuts against the mine wall when said cutting mechanism is being located in its initial position for another cut.

5. 62. A loading machine comprising a frame, an arcuate platform, an arcuate extension for said platform, and diametrically disposed pin and slot connections between said extension and said frame for permitting 10 lifting movement of said extension relatively to said arcuate platform and arcuate sliding movement relatively thereto.

15. 63. A loading machine comprising a frame, an arcuate horizontal platform connected thereto, an extension for said platform normally in arcuate alinement with said platform, and connections between said extension and said frame to permit said extension to be collapsed relatively to said 20 platform.

25. 64. A loading machine comprising a frame, an arcuate platform extending radially from said frame, an arcuate extension for said platform and normally in substantially the same plane of said platform and extending radially from said frame, the adjacent ends of said platform and said extension being beveled to direct said extension onto the top of said platform when said extension is moved circumferentially relatively to said frame, circumferential arms extending from said extension, and diametrically disposed pins projecting inwardly from the ends of said circumferential arms 35 and fitting in arcuate slots in said frame whereby said extension may have a vertical tilting movement on said pins relatively to said frame and an arcuate movement relatively to said frame to permit said extension 40 to be collapsed over the top of said arcuate platform.

45. 65. In a loading machine, the combination with a supporting frame, of a supplemental frame mounted for arcuate movement on said supporting frame about an upright axis, an arcuate platform extending radially from said supplemental frame and movable in an arc therewith, an arcuate extension for said arcuate platform mounted on said supplemental frame for circumferential movement relatively thereto, means for moving said supplemental frame in an arc on said upright axis to move said arcuate platform under a core of material in a mine wall, and 55 an abutment carried at the rear end of said extension for engaging the rear end of the core to automatically move said extension backwardly relatively to said arcuate platform and for engaging the mine wall to 60 move said extension in the opposite direction relatively to said platform.

65. 66. In a mining machine, the combination with a main frame comprising an upright standard free from obstructions between the ends thereof radially in every direction, of

a supplemental frame mounted for complete rotation about said standard as an upright axis and in horizontal planes substantially perpendicular to such axis, core-cutting mechanism having an unobstructed core-opening therethrough and mounted on said supplemental frame to rotate bodily therewith, means for operating said core-cutting mechanism including self-acting power mechanism for moving said supplemental frame on said standard through any angle relative to said standard and without changing the location of said standard or said upright axis, to effect arcuate feeding of said core-cutting mechanism, and self-acting power mechanism also mounted on said supplemental frame and connected to said main frame to adjust the elevation of said supplemental frame and said core-cutting mechanism vertically and rectilinearly along 85 said upright standard.

67. In a mining and loading machine, the combination with a main frame, a roof jack for securing said main frame in fixed position between the floor and roof of a mine chamber, a supplemental frame rotatable in either direction about said main frame and through any angle relatively thereto while said main frame remains in fixed position, loop chain core-cutting mechanism mounted on said supplemental frame in fixed radial relation to the upright axis of rotary movement of said supplemental frame and movable bodily with said supplemental frame, means mounted on said supplemental frame for actuating said loop chain core-cutting mechanism, means for moving said supplemental frame arcuately through any angle relatively to said main frame to feed said core-cutting mechanism during its actuation, 100 an arcuate platform extending radially from said supplemental frame in a plane below the core of material cut by said core-cutting mechanism and movable with the latter to extend under the core as it is being 110 produced, an arcuate extension for said platform, an abutment at the rear end of said extension, and connections between said arcuate extension and said supplemental frame for causing said extension to be moved in one direction when said abutment engages the rear end of the core and to be moved in the opposite direction in telescoping relation to said arcuate platform when said abutment engages the mine wall upon reverse feeding movement of said core-cutting mechanism.

68. In a mining machine, the combination with a supporting frame, of core-cutting mechanism having an unobstructed core-opening therethrough and mounted on said supporting frame, means for driving said core-cutting mechanism, means for feeding said core-cutting mechanism in horizontal planes to cut a core of material from an up- 130

right mine wall at relatively low elevation, and means for elevating the position of the core-cutting mechanism as a whole relatively to said supporting frame to cut a core also in the horizontal planes at a relatively high elevation.

69. In a mining machine, the combination with a supporting frame comprising an upright threaded standard, of a roof-engaging device projecting from the upper end of said standard, a hydraulic motor comprising a cylinder within said standard and a plunger depending from said roof-engaging device for forcing the latter against the roof to anchor the said frame including said standard, a supplemental frame mounted for rotation on said standard and for adjustment in elevation along said standard, cutting mechanism mounted on said supplemental frame and movable bodily therewith, means for driving said cutting mechanism, a motor carried by said supplemental frame, and gearing driven by said motor for causing said cutting mechanism to move longitudinally of said standard and angularly thereabout at the will of the operator.

70. In a mining machine, the combination with a supporting frame having an upright standard, of an upper extension on top of said standard comprising a cylinder at its lower end keyed to the interior of said standard to prevent rotation relative thereto, a roof-engaging device detachably connected to said extension and keyed to the upper end thereof to prevent relative rotation, a motor for operating said roof-engaging device, said motor comprising a cylinder in said extension and a plunger extending from said roof-engaging device into said cylinder, a supplemental frame adapted to be supported by said standard and by said upper extension, cutting mechanism carried by said supplemental frame, means for adjusting the elevation of said supplemental frame and cutting mechanism along said standard and along said extension, and means for feeding said cutting mechanism by moving said supplemental frame arcuately about said standard or said extension at the adjusted elevation of said cutting mechanism relative to said standard or said extension.

71. In a mining machine, the combination with a sectional roof-jack adapted to fit in different mine chambers having roofs of various heights, of means for operating said roof-jack to anchor the same rigidly in position, a frame threaded on said roof-jack for adjustment to various elevations along said roof-jack between the floor and roof of the mine chamber in which said roof-jack is anchored, cutting mechanism carried by said frame to move bodily therewith, means comprising the threaded connection between said frame and said roof jack for varying

the elevation of said frame and said cutting mechanism along said roof-jack, and means comprising a member slideable along said roof-jack but prevented from rotation relatively thereto, for moving said frame and said cutting mechanism arcuately relatively to said roof-jack to secure arcuate feeding movement of said cutting mechanism.

72. In a mining machine, the combination with a supporting frame, of a supplemental frame rotatably mounted on said supporting frame, cutting apparatus mounted on said supplemental frame to move bodily therewith, means for driving said cutting apparatus, means for swinging said supplemental frame relatively to said supporting frame to secure arcuate feeding movement of said cutting apparatus at a normal rate of speed, and means comprising brake-mechanism for effecting feeding movement of said cutting apparatus at varying lower rates of speed and more powerfully while said cutting apparatus is being driven at the same rate of speed as before, to cause said cutting apparatus to cut through abnormally hard material temporarily encountered by said cutting apparatus.

73. In a mining machine, the combination with a supporting frame, of a supplemental frame rotatably mounted on said supporting frame, cutting mechanism mounted on said supplemental frame to move bodily therewith, means for driving said cutting mechanism at a predetermined rate of speed, mechanism for rotating said supplemental frame relatively to said supporting frame to secure arcuate feeding movement of said cutting mechanism at a predetermined rate of speed, and means comprising brake mechanism for effecting feeding movement of said cutting mechanism at lower rates of speed and more powerfully while said cutting mechanism is being driven at its predetermined rate of speed to enable the latter to cut through hard material temporarily encountered.

74. In a mining machine, the combination with a supporting frame, of a supplemental frame mounted on said supporting frame for arcuate movement relatively thereto, cutting mechanism mounted on said supplemental frame, means for driving said cutting mechanism, means for moving said supplemental frame arcuately relatively to said supporting frame to secure arcuate feeding movement of said cutting mechanism, planetary gearing connected to said feeding means, and brake mechanism associated with said planetary gearing to render it effective to transmit slower and more powerful feeding movement to said cutting mechanism.

75. In a mining machine, the combination with supporting framework, of cutting mechanism mounted thereon, means for operating said cutting mechanism including

the feed thereof, planetary gearing connected to said feeding mechanism, and a brake associated with said planetary gearing to render the same effective to cause a slower and more powerful feeding movement of said cutting mechanism.

76. In a mining machine, the combination with supporting framework, of cutting mechanism mounted thereon, means normally operating said cutting mechanism including feed thereof, additional gearing connected between the source of power and the feeding mechanism, and a brake under the control of the operator for rendering said additional gearing effective to secure a slow and powerful feed of said cutting mechanism.

77. In a mining machine, the combination with supporting framework, of cutting mechanism mounted thereon, means for driving said cutting mechanism, means for feeding said cutting mechanism, a clutch for connecting the feeding mechanism to the source of power, planetary gearing connected to the source of power, and brake mechanism associated with said planetary gearing to enable the operator to connect the feeding mechanism to the source of power when said clutch is disconnected.

78. In a mining machine, the combination with a supporting frame comprising an upright standard, of a supplemental frame rotatable about said standard, cutting mechanism carried by said supplemental frame, means for driving said cutting mechanism, feeding mechanism, a motor, gearing for transmitting power from said motor to said feeding mechanism to effect, arcuate movement of said supplemental frame and said cutting mechanism, planetary gearing connected to said first-named gearing and to said feeding mechanism, a clutch for connecting said first-named gearing to said feeding mechanism, and brake mechanism for connecting said planetary gearing between said first-named gearing and said feeding mechanism while said clutch is disconnected.

79. In a mining machine, the combination with supporting framework, of cutting mechanism mounted thereon, means for operating said cutting mechanism comprising the feed thereof, planetary gearing, and means for connecting the planetary gearing to the feeding mechanism to secure slower and more powerful feed of said cutting mechanism.

80. In a mining machine, the combination with a cutter frame having upper and lower runs in substantially horizontal spaced-apart planes, and having an unobstructed core-opening between such runs, of means for supporting said cutter frame at various elevations while maintaining said runs in spaced-apart horizontal planes, kerf-cutting mechanism mounted on said runs,

and means for operating said kerf-cutting mechanism including movement of said cutter-frame to secure feeding movement of said cutting mechanism.

81. In a mining machine, the combination with a cutter frame having an unobstructed core-opening therethrough and upper and lower spaced-apart runs in horizontal planes, of a chain cutter mounted on said frames to travel around said unobstructed core-opening, means for supporting said cutter-frame and cutter at various elevations while maintaining said upper and lower runs in spaced-apart horizontal planes, and means for operating said chain cutter including the feed thereof by movement of said cutter frame.

82. In a mining machine, the combination with a supporting frame, of a loop chain core-cutter having upper and lower runs in fixed relation to each other as to a predetermined unobstructed core space between such runs, means for operating said core-cutter including arcuate feed thereof across the mine wall, and means for adjusting the height of said core-cutter in its entirety relatively to said frame while maintaining such predetermined core space, to cause the upper run to cut a kerf in a horizontal plane when in uppermost position and to cause the lower run to cut a kerf in a horizontal plane when in its lowermost position, the said fixed relation of the said runs causing a fixed relation of the kerfs cut by any one operation of the core-cutter whether an uppermost horizontal kerf is cut or whether a lowermost horizontal kerf is cut.

83. In a mining machine, the combination with loop chain core-cutting mechanism having upper and lower runs in horizontal planes, of means for adjusting the elevation of said core-cutting mechanism while permanently confining said upper and lower runs to horizontal cutting planes, and means for operating said core-cutting mechanism including arcuate feeding movement thereof at adjusted elevation.

84. In a mining machine, the combination with a main frame, of core-cutting mechanism having an unobstructed core-opening between upper and lower runs extending in horizontal planes, a supplemental frame for supporting said core-cutting mechanism for arcuate feeding movement on an upright axis, means for operating said core-cutting mechanism including arcuate feeding thereof on such upright axis, and mechanism between said main and supplemental frames for supporting said core-cutting mechanism at various elevations relative to said main frame while permanently confining the upper and lower runs of said core-cutting mechanism to feeding movements in approximately horizontal planes by maintaining said axis in upright position and while

said main frame remains in stationary position.

85. In a mining machine, the combination with a supporting frame, of chain-cutting mechanism for simultaneously cutting a plurality of kerfs in spaced-apart superposed horizontal planes, mechanism for adjusting the elevation of said chain-cutting mechanism while maintaining the same in position to cut in horizontal planes, and self-acting power-operated mechanism for operating said chain-cutting mechanism including swinging feeding movement thereof on an upright axis and relatively to said supporting frame to simultaneously cut such a plurality of kerfs in spaced-apart horizontal planes at adjusted elevations.

86. In a mining machine, the combination with cutting mechanisms, of a frame for supporting the same, a screw-threaded standard, a tube connected to said frame and fitting on said screw-threaded standard to guide said frame upwardly and downwardly, means for confining such up and down movement to a rectilinear movement by preventing relative swinging movement, a nut threaded on said standard, and means on said frame for rotating said nut to lift or lower said frame to adjust the elevation of said cutting mechanism while said tube guides said frame along said threaded standard.

87. In a mining machine, the combination with a supporting frame, of a loop chain core-cutter having an unobstructed core-opening therethrough and comprising a cutter frame, means for supporting said loop chain core-cutter on said first-named frame with the lower length of the chain cutter immediately above the floor of the mine chamber in position to cut in a horizontal plane, means for adjusting the elevation of said loop chain core-cutter including its frame, relatively to said first-named frame to vary the cutting plane of the lower length of the cutter above the floor of the mine chamber, and means for operating said chain core-cutter including feed thereof in any of its adjusted positions.

88. In a mining machine, the combination with a loop chain core-cutter having an unobstructed core-opening therethrough and having a substantially horizontal upper run and a substantially horizontal lower run, of supporting mechanism for said loop chain core-cutter, means for adjusting the core-cutter relatively to said supporting mechanism to vary the height of the entire core-cutter while maintaining the aforesaid runs substantially horizontal, and means for operating said core-cutter including the feed thereof in its various positions to which it has been adjusted in elevation.

89. In a mining machine, the combination of core-cutting mechanism having an

unobstructed core-opening therethrough and having parallel upper and lower lengths for cutting kerfs in substantially horizontal spaced-apart planes, of a main supporting frame, apparatus for bodily moving said core-cutter in its entirety to various elevations by moving the core-cutter in straight lines relatively to said main supporting frame, and means for operating said core-cutter including the feed thereof at the various elevations to which adjusted.

90. In a mining machine, the combination with a main frame, of a supplemental frame mounted on said main frame, of a loop chain core-cutter having an unobstructed core-opening therethrough and mounted on said supplemental frame to occupy a position in an upright plane, of means for adjusting the elevation of said core-cutter in its entirety relatively to said main frame, mechanism between said main and supplemental frames for confining such vertical adjustments to rectilinear up and down paths of movement, and means for operating said core-cutter including the feed thereof in its various adjusted positions.

91. In a mining machine, the combination with a main supporting frame, of a supplemental frame connected to said supporting frame, a loop chain core-cutter having an unobstructed core-opening therethrough and mounted on said supplemental frame, means for confining such adjusting movements to rectilinear paths of travel and thereby limit the adjustment of the position of said core-cutter to rectilinear paths of travel relatively to said supporting frame, and means for operating said core-cutter in its adjusted position including feed thereof to cut a core in a mine wall corresponding to such adjustment.

92. In a mining and loading machine, the combination with a main supporting frame, of a supplemental frame mounted on said supporting frame for up and down movement relative thereto, connections between said main and supplemental frames for confining such up and down movements of said supplemental frame to rectilinear paths of travel relatively to said supporting frame, a loop chain core-cutter mounted on said supplemental frame in any upright position to partake in its entirety of such rectilinear adjustments of said supplemental frame to secure upright rectilinear adjustment of the core-cutter in its entirety, and means for operating said core-cutter including the feed thereof to cut a core in a mine wall at an elevation corresponding to the adjustment of the elevation of said supplemental frame.

93. In a mining machine, the combination with a core-cutter having an unobstructed core-opening therethrough, of a supporting frame therefor, means for adjusting the height of said core-cutter by moving all

parts thereof relatively to said supporting frame up or down along vertical lines, and mechanism for operating said core-cutter including the feed thereof in its various positions to which it has been thus adjusted.

94. In a mining machine, the combination with loop chain core-cutting mechanism having an upper run straight in elevation and a lower run straight in elevation, of means for operating said loop chain core-cutting mechanism including the feed thereof, and means for adjusting the positions of said upper and lower runs to effect the cutting of the roof in a substantially horizontal plane and the cutting of the floor in a substantially horizontal plane.

95. In a mining machine, the combination with a supporting frame, of loop chain core-cutting mechanism mounted thereon and having an upper straight run for the roof cut and a lower straight run for the floor cut, and means for adjusting the elevation of the said upper and lower runs in accordance with the height of the mine vein.

96. In a mining machine, the combination with cutting apparatus, of supporting framework, a support for said framework together with the cutting apparatus mounted thereon, comprising a screw-threaded standard, means associated with said standard for adjusting the position of said cutting apparatus, and mechanism coacting with said adjusting means to hold the cutting apparatus at a predetermined height and effect the feed thereof.

97. The combination of cutting mechanism rotatable in one continuous direction and operable to sever a crescent-shaped section from the wall of a mine, a supporting platform rotatable therewith following said cutting mechanism and adapted to carry the severed section away from the mine wall, and a common supporting standard for supporting said platform and cutting mechanism at their centers of rotation.

98. The combination of cutting mechanism rotatable in one continuous direction and operable to sever a crescent-shaped section from the wall of a mine, and a supporting platform rotatable therewith following said cutting mechanism and adapted to carry the severed section away from the mine wall.

99. In a mining machine, the combination with a supporting frame, of an upright core-cutter pivotally mounted on said frame for arcuate feeding movement across a mine wall in a general horizontal direction, a supporting platform pivotally mounted on said frame for rotation of said core-cutter, and means for operating the supporting platform by moving the same arcuately relatively to said frame to carry the core in an arc approximately horizontally back from the mine wall.

100. In a mining machine, the combination with cutting mechanism having a horizontal cutting stroke and a support for the severed section of mine wall rotatable about a common center, of a pedestal supporting said cutting mechanism and said support at their center of rotation, said cutting mechanism and said support being bodily movable on said pedestal, and means for operating said cutting mechanism and support for dislodging sections of material from a mine wall and carrying them back from the mine wall at various heights between the floor and roof of the mine chamber in accordance with the adjustments of said pedestal.

101. The combination of a cutting mechanism bodily rotatable and arranged to sever a section from the wall of a mine, a support for said cutting mechanism, means for bodily moving said cutting mechanism on said support in an arc the plane of which is transverse to the plane of rotation of said cutting mechanism, a support for the severed section following said cutting mechanism and bodily movable therewith, and a pedestal supporting said cutting mechanism and support at their center of rotation and serving as a guide for the bodily movement thereof.

102. In a mining machine, the combination with a loop chain cutter, of means for operating the same to cut from a mine wall a crescent-shaped section of material, a segmental platform following and movable with said loop chain cutter to receive the said section of material and support the same, a segmental guiding strip carried by the inner portion of said platform, and means for moving said platform together with said guiding strip to carry said section of material back from the mine wall to a predetermined position.

103. In a mining machine, the combination with a main frame, of cutting mechanism for entirely severing from a mine wall a section of material, a supplemental frame rotatably mounted on said main frame and having a circular platform with an approximately semi-circular segment cut away ahead of said cutting mechanism, a vertical arc-shaped guiding strip on said platform and extending backwardly from the rear portion of said cutting mechanism, mechanism for feeding the cutting mechanism forward together with said platform, and apparatus for returning said cutting mechanism to initial position while moving said platform to cause the same to carry the severed section of material back from the mine wall.

104. In a mining machine, the combination with core-cutting mechanism, of means for operating the same including arcuate feed thereof, a frame for supporting said cutting means and said operating means, an

additional frame, a post extending from said additional frame through said supporting frame, and means for adjusting the position of said supporting frame on said post 5 to vary the height of said core-cutting mechanism.

105. In a mining machine, the combination with a supporting frame, of loop chain core-cutting mechanism, means for operating said loop chain core-cutting mechanism including lateral feed thereof, and means for adjusting the elevation of said loop chain core-cutting mechanism to effect the cutting of a plurality of cores one above another 15 between the floor and roof of the mine chamber leaving the surfaces of such floor and roof substantially horizontal, the lower and upper runs of said loop chain core-cutting mechanism being rectilinear in elevation, 20 and respectively in approximate horizontal planes when at the floor and at the roof.

106. In a mining machine, the combination with a supporting frame, of core-cutting mechanism mounted thereon, means for operating said core-cutting mechanism, a platform connected to said core-cutting mechanism and extending rearwardly therefrom to receive and carry the core cut by said core-cutting mechanism, means for reversing the movement of said core-cutting mechanism and said platform to carry the core rearwardly toward loading position and restore said core-cutting mechanism to initial position, and an abutment at the rear 35 end of said platform for engaging the rear end of said core.

107. In a mining machine, the combination with a supporting frame comprising an upright cylindrical bearing, of an auxiliary frame mounted on said supporting frame to rotate on said cylindrical bearing, loop chain core-cutting mechanism mounted on said auxiliary frame, means for operating said loop chain core-cutting mechanism including lateral arcuate feed thereof by movement of said auxiliary frame on said cylindrical bearing, a flat receiving table mounted on said auxiliary frame and having an arcuate segmental extension in position 45 to receive the core cut in the mine wall in the space originally occupied by said material, and an upright arcuate flange concentric with said cylindrical bearing and spaced back from the outer edge of said receiving 50 table extension.

108. In a mining machine, the combination with a main frame, of an upright post extending upwardly therefrom, mining mechanism comprising a supporting frame, means for pivotally supporting said supporting frame for rotating about said post, means comprising a screw-threaded rod extending through said supporting means to adjust the elevation of the latter together 60 with said mining mechanism and its sup-

porting frame, and means for rotating said mining mechanism about said post.

109. In a mining machine, the combination with a supporting frame, of loop chain core-cutting mechanism having an unobstructed core-opening therethrough and mounted on said supporting frame for swinging movement on an upright axis, means for operating said core-cutting mechanism including swinging thereof on said upright axis to secure the feed thereof, the upper and lower runs of said loop chain core-cutting mechanism being in spaced-apart planes each rectilinear in elevation, and means for adjusting the elevation of 80 said core-cutting mechanism on said supporting frame to secure the cutting of a roof in an approximately horizontal plane and the cutting of a floor in an approximately horizontal plane. 85

110. In a mining machine, the combination with a supporting frame, of core-cutting mechanism having an unobstructed core-opening therethrough with upper and lower spaced-apart runs rectilinear in elevation, said core-cutting mechanism being mounted on said supporting frame for swinging movement on an upright axis, means for supporting said core-cutting mechanism for up and down adjustment 90 relatively to said supporting frame to secure a position of the upper run of said core-cutting mechanism in an approximately horizontal plane when at the roof of the mine chamber and to secure a position of 100 the lower run of the core-cutting mechanism in an approximately horizontal plane when at the floor of the mine chamber, and means for operating said core-cutting mechanism including arcuate feeding movement thereof to cut arcuate cores from an upright mine wall and leave an approximately horizontal roof and an approximately horizontal floor. 105

111. In a mining machine, the combination with cutting mechanism, of means for operating said cutting mechanism to entirely cut out from the wall a section of material, a rigid device for said cutting mechanism to extend under a section of material as it is being cut in position for receiving the cut material from above, and means for operating said receiving device to cause the same to carry into loading position the section of material resting by gravity thereon. 110

112. In a mining machine, the combination with kerf-cutting mechanism for cutting spaced-apart kerfs and a communicating kerf back of a core of material in a mine wall, of means for operating said kerf-cutting mechanism to completely sever the core of material from the mine wall, a rigid device for supporting the core of material intact until after the entire core is completely severed from the mine wall, and means for operating said supporting device to move 115 120 125

back from the mine wall said core of material in its entirety.

113. A mining and loading machine comprising a supporting frame, means mounted thereon for cutting a U-shaped kerf in a mine wall in a general horizontal direction, conveyer mechanism in position for receiving the material as soon as it is dislodged by said cutting means, and means for operating said conveyer mechanism to effect the transfer of the dislodged material rearwardly toward loading position.

114. In a mining machine, the combination with a loop chain core-cutter having an upper straight run and a lower straight run, of means for operating said loop chain core-cutter including the feed thereof, and means for adjusting the elevation of said core-cutter as a whole whereby at the uppermost elevation a substantially horizontal kerf can be cut at the roof of the mine chamber, and at the lowermost position a substantially horizontal kerf can be cut at the floor of the mine chamber.

115. In a mining machine, the combination with a supporting frame, of a loop chain core-cutter having an upper straight run and a lower straight run, means for operating said cutter including the feed thereof, and means for adjusting the elevation of the core-cutter as a whole relatively to said supporting frame while maintaining the said upper and lower runs in the same relative positions to effect the cutting of the uppermost and lowermost kerfs in substantially horizontal planes at the floor and roof.

116. In a mining machine, the combination with a supporting frame, of a loop chain core-cutter having an upper straight run and a lower straight run, means for operating said cutter including the feed thereof to cut upper and lower spaced-apart kerfs and a communicating back kerf, and means for adjustably supporting the core-cutter to effect the cutting of the roof and floor kerfs in substantially horizontal planes in accordance with the said upper and lower straight runs of said loop chain core-cutter.

117. In a mining machine, the combination with a supporting frame, of a core-cutter having an unobstructed core-opening therethrough and having upper and lower runs rectilinear in elevation in position to cut plane kerfs, and means for adjusting said core-cutter as a whole rectilinearly and vertically relatively to said frame to effect the cutting of a plane floor kerf at one elevation and the cutting of a plane roof kerf at another elevation.

118. In a mining machine, the combination with a supporting frame, of a core-cutter having upper and lower runs rectilinear in elevation and having a forward cutting path of travel located in an upright plane, means for holding said core-cutter in such upright

plane in all positions thereof relative to said supporting frame, and means for adjusting the entire cutter rectilinearly and vertically relative to said frame to secure the cutting of a plane kerf at the floor of the mine chamber in one operation and the cutting of a plane roof kerf in another operation.

119. In a mining machine, the combination with a supporting frame, of cutting mechanism comprising means for cutting simultaneously spaced-apart horizontal parallel kerfs, means for operating said cutting mechanism, and means for vertically and simultaneously adjusting said cutting mechanism as a whole rectilinearly and relatively to said frame to effect the cutting of such spaced-apart kerfs at various elevations.

120. In a mining machine, the combination with a supporting frame, of a loop chain core-cutter having an upper straight run and a lower straight run in horizontal spaced apart parallel planes, means for operating said cutter including the feed thereof at adjusted elevation along a mine wall, and means for adjusting the elevation of the core-cutter rectilinearly as a whole relatively to said supporting frame while maintaining the said upper and lower runs in spaced-apart parallel horizontal planes to effect the cutting of the roof and floor in substantially horizontal planes.

121. In a mining and loading machine, the combination with a supporting frame movable in any direction at will from a given position in a mine chamber, of a mining machine comprising kerf-cutting mechanism operable to sever material in advance of said supporting frame in any direction in which said supporting frame may be moved, said mining machine comprising means for operating said kerf-cutting mechanism including arcuate feed thereof through any angle relatively to said supporting frame, and loading mechanism also carried by said supporting frame for receiving the severed material directly from its original position in the mine wall and transferring such material toward loading position.

122. In a mining machine, the combination with a receiving platform, of cutting mechanism at one end of said platform comprising means for cutting spaced apart kerfs, means for moving said cutting mechanism and said platform along a mine wall, a frame for supporting said receiving platform and said cutting apparatus, and means for adjusting the combined platform and cutting mechanism relatively to said main frame.

123. In a mining machine, the combination with a main frame, of a receiving platform mounted thereon, a loop core cutter located at one end of said platform, means for feeding said core cutter and platform to

dislodge a core section from a mine vein, and means for adjusting the position of said receiving platform and said core cutter together relatively to said main frame.

5 In testimony whereof I have signed my name to this specification, in the presence of

two subscribing witnesses, on this 3rd day of January, A. D. 1916.

EDMUND C. MORGAN.

Witnesses:

CHARLES H. SEEM,

A. J. CRANE.
